BOLT MECHANISM FOR FIREARM

Alonzo F. Gaidos, Redwood City, Calif.

Original application February 1, 1950, Serial No. 141,801.
Divided and this application December 8, 1952, Serial
No. 324,855

2 Claims. (Cl. 42—16)

(Granted under Title 35, U. S. Code (1952), sec. 266)

The invention described herein may be manufactured and used by or for the Government for governmental purposes without the payment of any royalty thereon.

The present invention relates to an improved bolt and firing pin mechanism for a lightweight automatic rifle and more particularly to the type of rifle as shown in my copending application, Serial No. 141,801, filed February 1, 1950 and now matured into U. S. Patent No. 2,688,203, of which this application is a division.

It is an object of this invention to provide improved means for retaining an impact type of firing pin in a reciprocable bolt without interfering with the slide utilized to return the bolt to battery position.

The specific nature of this invention as well as other objects and advantages thereof will clearly appear from a description of a preferred embodiment as shown in the accompanying drawings in which:

Fig. 1 is a fragmentary longitudinal cross-sectional view of the receiver and bolt with the striker in the cocked position;

Fig. 2 is a view similar to Fig. 1 but in the fired position and showing the means of attaching the barrel;

Fig. 3 is an enlarged cross-sectional view taken on line 3—3 of Fig. 4 showing the means of ejection;

Fig. 4 is a cross-section view taken on line 4—4 of Fig. 1;

Fig. 5 is an enlarged perspective view of the ejector; Fig. 6 is an enlarged view of the extractor;

Fig. 7 is a fragmentary perspective view of the rear end of the bolt;

Fig. 8 is a perspective view of the firing pin retainer; and

Fig. 9 is a cross-sectional view taken on line 9—9 of Fig. 2.

The particular embodiment of the invention, for the purpose of illustration as shown in the drawings, comprises a receiver 12, a bolt assembly 13, a breech block 14, and an actuating bar 15.

Receiver 12 is provided with a threaded longitudinal recess 16 in the upper rear end thereof to receive a striker retainer 17. The forward end of receiver 12 has a longitudinally protruding cylindrical boss 18 with exterior threads 19 for a purpose which will be explained later.

A longitudinal bore 20 is provided in the upper forward part of receiver 12 extending out through boss 18 and axially disposed therewith to slidably receive bolt assembly 13. Receiver 12 has a downwardly depending rectangular portion 21 being provided with a vertically disposed magazine opening 22 to receive a magazine 23. An angular slot 24 is also provided in portion 21 to receive breech lock 14 which will be later described.

Extending forwardly from threaded recess 16 of receiver 12 a longitudinal bore 25 is provided to receive a striker 26. Forwardly of longitudinal bore 25 a small

2

bore 27 is provided to slidably support a reduced end 28 on striker 26. Forwardly of bore 27 and connected to bore 20, an enlarged recess 29 is provided to receive a buffer 30. On the forward upper right side of receiver 12, angularly disposed above the axis, is a longitudinal slot 31 to permit ejection of a fired round and for the accommodation of a bolt handle 32. On the rear surface of receiver portion 21, a transverse slot 33 is provided to receive a retainer 34 of a bolt return spring rod 35. Rearwardly of portion 21 a depending lug 36 is provided with a transverse slot 37, complementary to slot 33, to receive a retainer 38 on the rear end of rod 35. A bolt return helical spring 39 surrounds bolt return spring rod 35 for a purpose to be later described.

Striker 26 comprises an enlarged diametrical rear end 40 that is slidably mounted in bore 25 and provided with an angular projection 41 on the bottom end thereof, forming a hook for the engagement of sears that are not more fully described as they form no part of this invention.

Bore 25 is provided with an opening in the bottom thereof to permit hook 41 to move therethrough and therealong and also admit sears therein. A cylindrical recess 42 is provided in the rear end of striker 26 to receive the forward end of a striker spring 43. Striker retainer 17 is provided with a knurled cylindrical head 45 to permit such retainer to be assembled in threaded recess 16.

A bolt 46 of bolt assembly 13, cylindrical in contour, is provided with a firing pin tunnel 47 therein to receive a firing pin 48 of a conventional shape, and such bolt is reciprocable in bore 20. Firing pin spring 49 surrounds pin 48 thereby biasing such pin rearwardly. Bolt

46 is provided on the rear end thereof with vertically positioned ways 50 to receive a firing pin retainer 51. Firing pin 48 has a reduced diametrical portion 52 on the rear end thereof which is slidably received in a hole 53 of retainer 51. Bolt 46 is provided with a longitudinal dove-tailed slot 54 on the forward right side angularly disposed above the horizontal axis to receive bolt handle 32. A longitudinal ejector slot 55 with a semi-cylindrical bottom is provided oppositely opposed to slot 54 on the left side of bolt 46 in the forward end thereof to slidably receive an ejector 56.

Bolt 46 is provided with a longitudinal shallow slot 57 rearwardly of and aligned with slot 54 to receive a bolt handle strap 58. Strap 58 is provided with a protruding detent 59 which nests in a recess 60 thereby retaining bolt handle 32 in position. Rearwardly of and aligned with slot 55 there is provided an ejector stop clearance longitudinal slot 61 to permit the free movement of bolt 46 in bore 20 of receiver 12. In the forward part of slot 55 there is provided a raised square lug 62 to limit the rearward movement of ejector 56. Ejector 56 has an elongated longitudinal notch 63 arranged for slidable engagement of lug 62 in slot 55. Ejector 56 is urged rearwardly by an ejector spring 64 which is assembled in slot 55 between a rear surface 65 of lug 62 and a rear surface 66 of notch 63. Bolt 46 is provided with a transverse slot 67 on the bottom rear end to receive lock 14.

Bolt handle 32 has a depending arcuate handle portion 68 for manually operating bolt 46. A longitudinal rectangular slot 69 is provided on bolt handle 32 to receive a spring-biased extractor 70 which is pivotally secured thereto by an extractor pin 71. Retainer 51 is provided with a rectangular open slot 72 on the bottom end thereof to permit a return bolt slide 73 to contact

bolt 46. Bolt return slide 73 is provided with a depending body portion 74 having an axial hole 75 therein. Bolt return slide 73 is slidably mounted on bolt return spring rod 35 by means of hole 75. Bolt return slide 73 is biased forwardly by bolt return spring 39 thereby urging bolt 46 into the battery position. Lock 14 is provided with a rectangular open slot 76 angularly disposed on the left side thereof for a purpose to be later described.

The invention as illustrated employs a barrel 77 that is provided with annular ribs 78 equidistant apart to effect cooling of the barrel. The rear end of barrel 77 is of reduced diameter as shown at 79 to slidably be received in bore 20 of receiver 12. Forwardly of end 79 an enlarged diameter portion 80 is provided to be rotatably received in a recess 81 of a barrel nut 82. The rear end of barrel nut 82 is provided with a threaded recess 83 for securing barrel 77 to the receiver 12 through the medium of threads 19 on receiver 12. The rear portion of the enlarged diameter 80 is provided with a longitudinal keyway 84 on the top and bottom thereof to receive a pair of keys 85 which are also receivable in slots 86 of boss 18 of receiver 12 to properly align and position the barrel 77 in the receiver 12 and also to prevent rotation of such barrel and insuring the maintenance of predetermined head space.

Receiver 12 is provided with vertically disposed ways 87 on the left side thereof juxtaposed to slot 24 to slidably receive actuating bar 15 for reciprocating movement therein. Actuating bar 15 is provided with oppositely disposed ribs 88 that are receivable in ways 87 of receiver 12. A lock actuating stud 89 is provided in the center and protrudes to the right of actuating bar 15 for a purpose to be described later. Oppositely disposed from stud 89, actuating bar 15 is provided with a lever 90 for manually operating lock 14 for a purpose to be described. An elongated longitudinal slot 91 is provided on the left side of a stock 92 to permit movement of lever 90 therealong. Receiver 12 is secured in a stock 92 by trigger guard 93. A forestock 94, pivotally mounted to a front barrel band (not shown), is secured to stock 92 by latching means 95. Forestock 94 is provided with a rectangular longitudinal slot opening 96 from the top on the rear end thereof to receive a barrel nut lock 97 which is secured to the bottom surface thereof by conventional wood screws. Barrel nut lock 97 is provided with a resilient upstanding tooth 98 which cooperates with longitudinal serrations 99 on barrel nut 82 whereby such nut secures barrel 77 at the proper head space in relation to bolt 46 and thereby secures such barrel to receiver 12. A narrow longitudinal slot 100 is provided forwardly of slot 96 in forestock 94 to accommodate a rod 101 that is coupled to actuating bar 15. Actuating bar 15 when coupled to rod 101 is spring-biased rearwardly by spring means (not shown) thereby camming the lock 14 upwardly and locking the bolt 46 in the battery position and such bar is also actuated forwardly by gas pressure accumulating in an actuating cup (not shown) thereby camming the lock 14 downwardly and unlocking the bolt 46 from the battery position.

Operation

After the insertion of magazine 23, loaded with double row of cartridges 102, into the magazine opening 22 of receiver 12 and secured therein by a latch 103, lock 14 then is angularly cammed downwardly out of slot 67 of bolt 46 by pressing forwardly on lever 90 with the thumb of the left hand, such lever being on the left side of the rifle. The bolt assembly 13 is then retracted to the rear by handle 32 permitting the uppermost cartridge 102 in the magazine 23 to enter the chambering space between the bolt 46 and the end of the barrel 77 whereby on the return of the bolt to the battery position, the round is chambered in the barrel and the gun is charged for firing. After discharge of the cartridge 102 and when a conventional bullet has cleared the bore

at the muzzle end (not shown) and while passing through the actuator, cup, (also not shown), the gases escaping from such bore impinge upon the inner wall of such cup that is coupled with the actuating bar 15 which in turn moves such bar forwardly thereby camming the lock 14 downwardly permitting the bolt assembly 13 to recoil. When the bolt assembly 13 moves rearwardly in recoil, ejector 56 comes in contact with an ejector stop 104 secured to receiver 12 and protruding into bore 20 whereby ejector 56 stops in relation to the bolt 46 thereby ejecting spent cartridge 102 out of the receiver 12 through slot 31. At the end of the recoil strike, the bolt assembly 13 is returned to the battery position under the bias of spring 39 picking up the uppermost cartridge 102 from the magazine 23 and chambering same in the barrel. At the end of the counter-recoil cycle, actuating bar 15 moves lock 14 up into the locking position.

It will, therefore, be apparent to one skilled in the art that application of the principle of the invention disclosed herein provides novel and improved firearm construction which is outstandingly characterized by a small number of parts with simplicity of configuration by such parts and also in cheapness of manufacture.

I claim:

1. In a firearm having a receiver and a bolt slidably mounted therein for reciprocal movement between a battery and a recoil position, the bolt having a firing pin tunnel axially therethrough and an intersecting vertical T-slot in the rear end thereof, a longitudinal firing pin slidably seated in said tunnel, a firing pin retainer disposed in said T-slot and having a longitudinal hole therethrough coaxial with said firing pin tunnel but of lesser diameter relative thereto, said firing pin having a rear end portion of reduced diameter, spring means normally urging said firing pin rearwardly into contact with the forward face of said retainer with said reduced end portion extending through said retainer to project beyond the rear face thereof, said retainer having a vertical slot extending along the underside thereof to provide access to the rear wall surface formed by said T-slot in the bolt, a bolt return slide having a substantially rectangular front end portion adapted to normally extend through said retainer slot into said T-slot to contact the bolt, spring means normally urging said bolt return slide forwardly to maintain the bolt in the battery position thereof, and striker means adapted to actuate said firing pin forwardly when said bolt is in the battery position.

2. In a firearm having a receiver and a bolt slidably mounted therein for reciprocal movement between a battery and a recoil position, the bolt having a firing pin tunnel axially therethrough and an intersecting T-slot extending vertically along the rear end thereof, a longitudinal firing pin slidably seated in said tunnel, a firing pin retainer disposed in said T-slot and having a longitudinal hole therethrough coaxial with said firing pin tunnel but of lesser diameter relative thereto, said firing pin having a rear end portion of reduced diameter, spring means normally urging said firing pin rearwardly into contact with the forward face of said retainer with said reduced end portion of said firing pin extending through said retainer to project beyond the rear face thereof, said retainer having a vertical slot along the underside thereof to provide access to the rear wall surface formed by said T-slot, a longitudinal rod fixedly secured at either end in the receiver below the reciprocating path of the bolt, a bolt return slide comprising a body and an arm projecting forwardly from the upper end of said body, said arm having a substantially rectangular front end portion projecting upwardly therefrom and adapted to normally extend through said retainer slot into contact with the rear wall surface of said T-slot, said bolt return slide having a hole through the body thereof for slidably receiving the forward end of said longitudinal rod therethrough, spring means surrounding said rod in abutment with the rear end of said bolt return slide body for nor-

mainly urging said slide forwardly to maintain the bolt in the battery position thereof, and a striker slidably disposed in the receiver in axial alignment with said firing pin, said striker adapted to be released from a retracted position for contact with the rear end of said firing pin 5 projecting beyond said firing pin retainer in the battery position of the bolt whereby said firing pin is actuated forwardly to discharge the firearm.
